(57) **CLAIM**

The ornamental design for a light emitting diode (LED) ceiling light, as shown and described.

DESCRIPTION

FIG. 1 is a Perspective View of the light emitting diode (LED) ceiling light of the claimed design.

FIG. 2 is a Front View of the light emitting diode (LED) ceiling light.

FIG. 3 is a Rear View of the light emitting diode (LED) ceiling light.

FIG. 4 is a Left Side View of the light emitting diode (LED) ceiling light.

FIG. 5 is a Right Side View of the light emitting diode (LED) ceiling light.

FIG. 6 is a Top Plan View of the light emitting diode (LED) ceiling light.

FIG. 7 is a Bottom Plan View of the light emitting diode (LED) ceiling light; and,

FIG. 8 is a Reference Perspective View showing a decomposition state of the light emitting diode (LED) ceiling light.
